UNITED STATES PATENT OFFICE.

JOSEPH Perna, OF PHILADELPHIA, PENNSYLVANIA.

DREDGING-HOIST TROLLEY.

Application filed July 21, 1919. Serial No. 312,418.

To all whom it may concern:

Be it known that I, JOSEPH Perna, a citizen of the United States, residing at Philadelphia, in the county of Philadelphia and 5 State of Pennsylvania, have invented a new and useful Improvement in Dredging-Hoist Trolleys, of which the following is a specification.

My invention relates to a new and useful 10 improvement in dredging hoists and trolleys therefor and automatic mechanism for actuating the same, and has for its object to so construct and arrange an apparatus of this description as to provide for the lowering 15 and raising of the dredging member, which latter is preferably of the type of what is known as the clamshell dredge, locking said dredge in its elevated position, so as to take the weight thereof off the cable, and automatically unlocking the dredging member, 20 and permit it to be lowered by slackening the cable.

A further object of my present invention is to provide for supporting the operating 25 cable at a number of points through its length, so as to prevent the undue sagging thereof.

A still further object of my invention is to provide for the cable supporting mechanism 30 to be automatically released from the cable, and returned to the support thereof by the travel of the trolley carrying the dredging member.

With these ends in view, this invention 35 consists in the details of construction and combination of elements hereinafter set forth, and then specifically designated by the claims.

In order that those skilled in the art 40 to which this invention appertains may understand how to make and use the same I will describe its construction in detail, referring by numerals to the accompanying drawing forming a part of this application, 45 in which:—

Fig. 1 is a side elevation of the overhead trolley track the trolley located thereon, and the dredging member suspended therefrom.

Fig. 2 is an end view of the trolley track

showing a portion of the posts and beams 50 by which it is supported, the dredging member being omitted.

Fig. 3 is a detail edge view of the hanger to which the dredging member is pivoted. 55

Fig. 4 is a detail plan view of one of the cable supporting members.

Fig. 5 is a side elevation of a portion of the dredging member and trolley, one of the side plates of the trolley being removed to 60 clearly show the manner in which the hanger passes into contact with the supporting cam.

Fig. 6 is a view similar to Figure 5 showing the upper end of the hanger in the position it assumes when it has finally entered into engagement with the cam hook. 65

Fig. 7 is a view similar to Fig. 5 showing the hanger in the position it assumes when the cable is drawn back to release 70 said hanger from the cam hook.

Fig. 8 is a view similar to Fig. 5 showing the hanger in the position it assumes after passing out of contact with the cam hook, and just prior to the dredging member being lowered by the slack of the cable. 75

In carrying out my invention as here embodied, 1 represents one of a series of posts for supporting the overhead trestle 2, which may be of any desired length, and has depending therefrom the I-beam 3, the lower flanges of which serve as tracks for the trolley wheels 4, journalled to the trolley 5. This trolley consists of two side plates, bolted together in any well known or convenient 85 manner, on the inner surface of each of which is located one of the supporting cams 6, each being located diametrically opposite each other, for the purpose hereinafter set forth. 90

Between the two side plates of the trolley is journalled a shive wheel 7 over which the operating cable 8 runs, said cable passing downward around the shive wheel 9 and again upwards its end being secured to the 95 stud 10 in said trolley.

The shive wheel 9 is journalled between the side bars and the hanger 11, which hang-

er is pivoted at 12 to the top of the clam shell dredge 13, and from the sides of the upper end of this hanger project the studs 14 adapted to pass into engagement with 5 the supporting cams 6.

15 represents a tail rope or out haul cable, one end of which is attached at 16 to the trolley, while the other end is secured to a suitable winding drum. Thus it will be seen 10 that by the proper manipulation of the cable and tail rope, the trolley may be caused to travel along its track to a point where it is desired to put the dredge into operation, and by slackening on the cable, the dredge 15 will be lowered, and when loaded the drawing of the cable will hoist the dredge until the studs 14 come in contact with the ends of the supporting cams, and a continuation 20 of this hoisting will cause these studs to ride up to the under side of said cams as clearly shown in Fig. 5 until passing over the point thereof. Now by a slight slackening on the cable, the studs will be lowered into the hook of the cams, which will therefore 25 support the dredge and its load, releasing the strain from the cable, after which the trolley may be drawn by the tail rope to the point of discharge, when by again drawing 30 on the cable, the studs will ride up the inner face of the supporting cams as shown in Figure 7, until passing over the upper point thereof the hanger will assume the 35 position shown in Fig. 8. Now by slackening upon the cable the dredge may be lowered to the desired point for discharging its load, leaving the mechanism in position for repeating these operations.

In utilizing the principle here involved 40 and above described, both the cable and the tail rope during certain of the operations tend to sag to a degree that would interfere with the operations, and it is therefore necessary to provide means for supporting said cable and tail rope at intermediate points, 45 and such supports must be manipulated by automatically passing out of the path of the trolley in its travels back and forth, and I accomplish this object by depending a series of brackets 17 from the top of the 50 I-beam, on which is supported a runner 18, and at convenient intervals along this runner are pivoted the arms 20, as indicated at 21. Each of the arms 20 has a relatively long roll 21 journalled thereon, and two coil 55 springs 22 attached thereto, the opposite ends of said springs being attached to the runner as indicated at 23, so as to normally hold the arm of this roll at right angles to the runner, as shown in Fig. 4.

60 These rolls are so disposed that they lie beneath the cable and tail rope, thus supporting the same against undue sagging, and yet as the trolley travels to and fro, it will automatically swing these rolls to one side 65 or the other, but immediately upon the

trolley passing an arm its springs will return it to its normal position beneath the cable and tail rope.

Thus it will be seen that regardless of the length of the cable and tail rope, no undue 70 sagging will take place, obviating the necessity of using the usual chain spaced hangers which are expensive, annoying and at times exceedingly dangerous to the workmen.

75 Of course I do not wish to be limited to the exact details of construction as herein shown, as these may be varied within the limits of the appended claims without departing from the spirit of my invention.

80 Having thus fully described my invention, what I claim as new and useful is:—

1. In an apparatus of the character described a trolley, means for supporting said trolley, a hanger pivoted to the dredge, a 85 cable so attached to the trolley as to have a loop formed therein, a shive wheel journalled in the hanger, over which the loop in said cable runs, a stationary supporting cam carried by the trolley, and means for causing said hanger to so enter into engagement with the surfaces of said supporting cam as to be locked thereon and unlocked therefrom.

2. In an apparatus of the character described, a trolley adapted to travel upon an overhanging track, a cable attached to said trolley in such manner as to form a loop in said cable a dredge, a hanger pivoted thereto, a shive wheel journalled in said 100 hanger over which latter runs the loop in the cable, studs projecting from the sides of the hanger, and double stationary supporting cams carried by the trolley, of such shape that the contacting of said studs therewith will lock the hanger to the cam or free it therefrom by certain manipulations of the cable.

3. In combination with a trolley of the character described, a double stationary supporting cam secured thereby, a shive wheel journalled in the trolley, a cable passing over said shive wheel, one end thereof secured to said trolley, a dredge, a hanger pivoted to said dredge, a shive wheel journalled in 115 the hanger, around which latter shive wheel said cable passes, and studs projecting from the upper end of the hanger adapted to enter into various engagements with the supporting cam, whereby the hanger may be 120 automatically locked to said cam and released therefrom by the manipulation of the cable.

4. A device of the character stated, comprising a trolley, oppositely disposed fixed 125 cams carried thereby, each having a hook formed with the lower portion thereof, in combination with a dredge bucket, a hanger pivoted to the bucket for supporting the same, studs carried by the hanger and means 130

for supporting said hanger adapted to raise and lower the same, said studs, when moved into contact with the cams, sliding along the under surface of the hook portions and then 5 dropping into said hook portions and when raised for disengagement from the cams, sliding along the inner surface thereof until they ride over the upper ends thereof after which said studs slide down over the outer surfaces of said cams, as shown and 10 described.

In testimony whereof, I have hereunto affixed my signature.

JOSEPH PERRA.
